UNITED STATES PATENT OFFICE

2,136,590

SHOE SEWING MACHINE

Bernard T. Leveque, Wenham, Mass., assignor to
United Shoe Machinery Corporation, Paterson,
N. J., a corporation of New Jersey

Original application March 12, 1935, Serial No.
10,621. Divided and this application May 12,
1936, Serial No. 79,285

16 Claims. (Cl. 112—58)

The present invention relates primarily to shoe sewing machines, and is herein disclosed as embodied in a curved hook needle lockstitch machine adapted to sew the outsole to the welt and upper of a welted shoe, the illustrative embodiment of the invention being of the same construction and operation as that of the machine described in applicant's pending application Serial No. 10,621, filed March 12, 1935, of which

10 the present application is a division.

The objects of the invention are to produce an outsole shoe sewing machine having its various parts constructed and arranged to operate in an improved manner so as to permit the machine 15 to be run at a speed high as compared with the speed of machines of this type at present in commercial use, while feeding the shoe and manipulating the needle and locking threads so as to produce a satisfactory seam having stitches evenly 20 spaced and formed in a predetermined uniform manner.

With the above objects in view, a feature of the invention relates to an improved mechanism for handling the needle and locking threads during 25 the formation of a stitch. In accordance with this feature of the invention, a locking thread measuring or pull-off mechanism is provided comprising a thread gripping device, and this gripping device is so timed and actuated that it is 30 in gripping engagement with the locking thread at the time the needle thread is being pulled into its final position to set the stitch so that the position of the lock is accurately determined by the resistance to further movement of the locking 35 thread into the work as soon as the amount previously pulled from the locking thread case by the gripper has been pulled into the work by the loop of needle thread.

In order to secure an even and uniform positioning of the lock in the work, regardless of 40 variations in the length of the stitches occasioned either by irregularities in the action of the feeding mechanism or by an initial adjustment of the feeding mechanism, a feature of the invention 45 contemplates pulling from the locking thread case during the formation of each stitch a length of thread varying with variations in the length of the stitches. This feature of the invention is embodied in the machine hereinafter described 50 in mechanism for varying the throw of the thread gripping jaws above referred to. This feature of the invention contemplates varying the throw of the pull-off device for a locking thread in any desired manner, but in the machine hereinafter described, this result is secured by actuating the

thread measuring gripper through a connection to the work feeding mechanism.

The locking thread pull-off or measuring mechanism, above referred to, is well adapted to cooperate with the take-up and needle thread tension devices commonly used in lock-stitch sewing machines. To still further improve the thread handling devices of the machine so as to prevent breaking of thread or irregularities in the stitches by reason of faulty handling of the needle thread, 10 the present invention also contemplates using, in combination with the locking thread pull-off or measuring mechanism, a pull-off and measuring mechanism for the needle thread, whereby the proper amount of needle thread is supplied to 15 the take-up by the thread measuring mechanism and the full tension is not exerted on the needle thread until the locking thread has been drawn a predetermined distance into the work.

Certain features of the present invention also 20 consist in novel and improved devices, combinations and arrangements of parts hereinafter described and claimed, the advantages of which will be obvious to those skilled in the art from the following description. Certain of these devices, 25 combinations and arrangements of parts, while particularly adapted for use in outsole shoe sewing machine, are capable of use in other types of machines and, accordingly, the several features of the invention are not to be considered as limited to any particular application except as specifically defined in the claims.

An outsole shoe sewing machine embodying the several features of the present invention is illustrated in the accompanying drawings, in 35 which Figure 1 is a view in side elevation of the head of the machine; Figure 2 is a detail sectional view of the rotary loop taker which is in the form of a shuttle, together with the thread case and bobbin for the locking thread supported therein; 40 Figure 3 is a view in front elevation of the head of the machine illustrated in Figure 1; Figure 4 is a detail view in side elevation of the sewing devices adjacent the sewing point; Figure 5 is a detail sectional view of the mechanism illustrated in Figure 4; Figure 6 is a detail sectional view on a larger scale of certain of the parts illustrated in Figure 5; Figure 7 is a detail view in front elevation of the thread finger and looper; Figure 8 is a plan view of the mechanism illustrated in Figure 7, together with the actuating lever for the looper; Figure 9 is a detail view in front elevation, partly in section, illustrating the work feeding mechanism and the take-up mechanism for the needle thread; Figure 10 is a plan 50 55

view of the work feeding mechanism; Figure 11 is a view in front elevation of the mechanism illustrated in Figure 10; Figure 12 is a detail view illustrating the connection between the feeding mechanism and locking thread pull-off or measuring mechanism; Figures 13 to 22 inclusive are a series of detail views illustrating the operation of the thread handling devices in forming a stitch; Figure 23 is a detail sectional view illustrating in side elevation the take-up, pull-off and thread lock for the needle thread, together with their actuating and controlling mechanisms; Figure 24 is a detail view of a portion of the mechanism illustrated in Figure 23, but looking in the opposite direction and with the parts in a different position; Figure 25 is a plan view of the parts illustrated in Figure 24; and Figure 26 is a detail sectional view illustrating particularly the presser-foot actuating and controlling mechanism.

The work feeding mechanism illustrated in the drawings is of that type in which the work is fed intermittently by the cooperating action of a work support and presser foot constructed and arranged to engage respectively the welt and out-sole of a shoe. Referring particularly to Figures 9 to 12, the work support is indicated at 2 and the presser foot at 4, both of these parts being mounted upon a feed carriage in the form of a slide 6 mounted for advancing and retracting movements in the line of feed on fixed guides 8 and 10. The work support 2 is rigidly secured to an arm projecting forwardly from the slide 6 and the presser foot is secured to the forwardly extending arm of a presser foot lever 12 pivotally mounted upon the slide 6. The lever 12 is connected to the cam shaft of the machine through mechanism hereinafter described, by which the lever is actuated to cause the work to be gripped between the presser foot 4 and the work support 2 and to be released during each stitch forming cycle of the machine. The feed slide 6 is advanced and retracted in the line of feed during each stitch forming cycle by the mechanism to be described, said mechanism being similar to that disclosed and claimed in applicant's pending application Serial No. 10,621 above referred to, and these movements are timed with relation to the movements of the presser foot lever 12, so that the advancing movement to feed the work takes place while the work is clamped, and the retracting movement takes place while the work is released. The work is thus fed past the stitch forming devices of which the curved awl and the curved hook needle are indicated respectively at 14 and 16.

For imparting the advancing and retracting movements in the line of feed to the feed carriage 6, a toggle is provided comprising the members 18 and 20. These members are connected by the central pivotal joint 22. The member 18 is pivotally connected at 24 to the feed slide 6, and the member 20 is pivotally connected at 26 to a support 28. The pivotal centers 24, 22 and 26 are so arranged that when these centers are in line, the feed slide 6 is at the extreme limit of its advancing feeding movement. The feed slide is actuated by reciprocating the central joint 22 of the toggle and, to this end, the member 18 of the toggle is connected by means of a link 30 to the upper end of a pivotally mounted supporting arm 32 which is actuated from the cam shaft of the machine through connections including a link 34 also connected to the upper end of the arm 32.

To vary the action of the toggle so as to vary the feeding movements imparted to the slide 6,

the support 28 which carries the pivotal center 26 of the toggle is pivotally mounted in alignment with the central joint 22 of the toggle when the toggle is in straightened condition, and means are provided for adjusting the support 28 about its pivot so as to change the position of the pivotal center 26. As will be apparent from an inspection of Figure 10, an adjustment of the support 28 in a counter-clockwise direction will act to increase the length of feeding movements, while an adjustment of the support 28 in a clockwise direction from the position indicated in Figure 10 will act to decrease the length of feeding movements.

As a convenient means for adjusting the support 28 and holding it securely in adjusted position, the support is provided with a gear segment 36 which meshes with the gear segment 38 upon the inner end of the adjusting lever 40 pivotally mounted upon a stud 42 secured to a fixed portion 44 of the machine frame. At its outer end the lever 40 extends over a segmental plate 46 provided with perforations 48 in which pins may be inserted to limit the swinging movement of the lever 40 in adjusting the support 28.

To hold the adjusting lever 40 in any position to which it may be moved, a clutch mechanism is provided comprising two one-way clutch rolls 50 seated in recesses in a block 52 secured to the outer end of the adjusting lever 40 and interposed between a segmental surface 54 on the outer edge of the plate 46 and inclined surfaces 56 on the block 52. A coiled spring 58 extending through a block 60 at the lower end of a stud secured in the lever 40 and interposed between the balls 50 normally acts to force the balls away from each other into clutching position so that the adjusting lever 40 is held from movement in one direction by one ball and from movement in the other direction by the other ball.

The clutching mechanism is controlled and the adjusting lever 40 is actuated by a control lever 62 which is mounted upon the stud 42 and extends outwardly over the lever 40 and over the clutch mechanism. At its outer end the control lever 62 is provided with arms 64 which extend downwardly outside of the balls 50 and are provided at their lower ends with set screws 66 arranged, when the lever 62 is swung in either direction, to engage one or the other of the balls 50 and move it into inoperative position against the tension of the spring 58. The control lever 62 thus has a limited movement independently of the adjusting lever 40 and acts during this limited movement to actuate the clutch mechanism to release the adjusting lever 40. Continued movement of the control lever 62 in the same direction thereafter acts to move the adjusting lever. A spring pressed plunger 68 mounted in the adjusting lever 40 is arranged to engage a recess in the lower surface of the control lever 62 and hold the control lever normally out of engagement with the clutch rolls.

The curved awl 14 and the curved hook needle 16 are clamped respectively in the awl segment 70 and the needle segment 72, which segments 65 are mounted to oscillate concentrically upon a fixed stud 74 supported in brackets 76 and 78 fixed to the frame of the machine. The needle and awl segments are so supported that the needle and awl are in the same vertical plane 70 and operate in this plane without any movement back and forth in the direction of feed. The needle guide indicated at 80 is secured to a hub 82 and this hub is also supported from the stud 74. The needle and awl segments are actuated, 75

as hereinafter described, to cause the needle and awl to enter and withdraw from the work. The movements of the awl segment tend to move the needle guide through frictional engagement with the hub of the guide and the guide is thus actuated in the desired manner.

In addition to the needle, the thread handling devices acting on the needle thread consist of a needle threading looper, a thread arm for drawing out a bight of thread between the looper and the work, a loop taker in the form of a shuttle for passing a loop of needle thread over the locking thread case, a loop spreader to spread the loop for the loop taker, a take-up, a thread lock and a needle thread pull-off or thread measurer.

The looper comprises a thread eye 84 formed (see Figs. 3, 4, 5, 7 and 8) in the outwardly bent arm of a rod secured so as to be capable of longitudinal adjustment in an axial socket at the upper end of a downwardly and rearwardly extending shaft 86. The shaft 86 is mounted in a fixed bracket 88 and is provided at its lower end with a gear segment 90, meshing with a gear segment 92 at the forward end of an actuating lever 94. This lever is pivotally mounted on the machine frame and is oscillated from the cam shaft of the machine through connections hereinafter described. While the needle is through the work, the looper, in cooperation with the thread arm, is oscillated to carry the thread outside of and across the circle of the needle to thread the needle, as clearly shown in Figures 17 and 18.

The thread finger, indicated at 96, is secured to the upper end of a lever 98 pivoted at its lower end upon the fixed bracket 88 and arranged to swing in a vertical plane across the upper end of the looper when the looper is in the position indicated in Figures 7 and 8. As the needle makes its work piercing stroke the thread finger is moved rearwardly across the top of the looper and draws out a bight of thread between the looper and the work, as indicated in Figures 17 and 18. The mechanism for actuating the thread finger will be hereinafter described.

The loop spreader (see Figs. 3, 4 and 14 to 22) comprises an arm 100 secured to a block 102 integral with a laterally extending stud 104 journaled in fixed bracket arms 106 and 108 (see particularly Fig. 3). The lower end of the loop spreading arm projects slightly across the plane of the needle and when actuated moves from its rearward position forwardly across the path of the needle to engage one side of the needle loop and extend it to the position indicated in Fig. 19. The loop spreader is actuated from the cam shaft of the machine through connections hereinafter described which comprise a lever arm 110 clamped to the supporting stud of the spreader carrying block 102 between the fixed brackets 106, 108.

The loop taker, which takes the spread loop from the needle and loop spreader and passes it over the thread case for the locking thread is indicated at 112 (see Figs. 2, 6, and 13 to 22). This loop taker is in the form of a discoidal rotary shuttle which passes completely through the needle loop. It comprises a hollow cylindrical body closed at its rear end and open at its forward end to receive the cylindrical locking thread case 114. This locking thread case is loosely mounted upon a supporting stud 116 extending forwardly from the rear wall of the shuttle and forming a bearing for the sleeve 118 projecting rearwardly from the rear wall of the

thread case. The sleeve 118 forms a bearing for a bobbin 120 on which the locking thread is wound. The locking thread leads from the bobbin through a passageway 122 in the cylindrical wall of the thread case and then passes diametrically across the outer front face of the thread case along passageways formed in a projection 124 at the top of the thread case and a projection or nose 126 at the bottom of the thread case. The shuttle body at its inner and outer ends is provided with beveled surfaces to facilitate the passage of the needle loop over the shuttle, and between these surfaces is provided with a bearing groove engaged by a circular raceway 128 by which the shuttle is supported in the machine. As shown in Figs. 5 and 6, the raceway 128 is provided with channels 130 through which lubricating oil is supplied to the bearing surfaces of the shuttle. The periphery of the shuttle is interrupted by a recess shaped to receive a shuttle driving arm 132 and to form the loop taking beak 134 and heel 136.

During the operation of the machine, the shuttle is rotated continuously in the same direction and the locking thread case is held from rotation by a retaining arm 138, the lower end of which is provided with a notch engaging the nose 126 at the bottom edge of the case. To provide ready access to the thread case, the retaining arm 138 is pivotally mounted on the frame of the machine near its upper end by means of a pivot shaft 140 so that the lower end of the retaining arm may be swung outwardly away from the thread case, as indicated in dotted lines in Figure 1. The retaining arm is normally held in retaining position in front of the thread case by means of a pivotally mounted latch 142 arranged to engage a projecting pin 144 at the upper end of the retaining arm above the pivot shaft 140. A spring 146 stretched between the latch 142 and the upper end of the arm 138 serves to retain the latch in engagement with the pin 144 until the latch is raised by the operator when the spring acts to swing the retaining arm away from the thread case.

After the needle loop is carried over the top of the shuttle, it is pulled down from the shuttle and into the work by the take-up mechanism illustrated particularly in Figures 9, 23, 24 and 25. This take-up mechanism comprises two arms 148 and 150 pivotally mounted one above the other to swing in substantially the same vertical plane. At their outer ends these arms carry respectively take-up rolls 152 and 154 over which the needle thread passes in its travel from the source of supply to the looper. In taking up the thread, the take-up rolls 152 and 154 cooperate with fixed guide rolls 156 and 158, these guide rolls being arranged so that the thread coming from the supply passes first around the roll 156, then over the upper take-up roll 152, then over the lower take-up roll 154, then upwardly to the guide roll 158 and from this roll to the looper. The take-up arms 148 and 150 are arranged to move from the position indicated in Figure 24, in which they are substantially horizontal and parallel, to the position indicated in Figure 23, in which they are substantially vertical and in line with each other. In so moving, the arms 148, 150 cause the take-up rolls 152 and 154 to take up the thread simultaneously in two loops and, by reason of the fact that the arms are substantially in alignment at the limit of their taking-up stroke, the amount of thread taken up is always the same, and is not affected by any overthrow of the arms. The take-up arms are actu-

ated from the cam shaft of the machine through mechanism hereinafter described, which mechanism comprises intermeshing gear segments 160 on the hubs of the arms, a gear segment 162 on the hub of the lower arm 150, and a gear segment 164 meshing with the gear segment 162 and carried at the outer end of one arm of a lever 166.

In the operation of the machine illustrated in the drawings, the depth to which the loop of needle thread is drawn into the work by the take-up is determined primarily by a thread measuring and gripping mechanism acting on the locking thread. This locking thread measuring or pull-off mechanism is best illustrated in Figures 3, 4, 5, 6, 12 and 13 to 22, and comprises two gripping jaws 168 and 170 arranged to act on the locking thread between the projections 124 and 126 on the face of the thread case. The jaws have a reciprocating movement back and forth along the lead of the thread and the jaw 170 has a movement towards and from the jaws 168 to cause the jaws to grasp and release the thread. To give the jaws these movements, the jaw 168 is mounted rigidly on the lower end of a slide 172 and the jaw 170 is pivotally mounted upon the slide. The jaws 168 and 170 are located directly in front of the thread case and, in order to provide for the removal of the jaws from in front of the thread case so as to permit access to the locking thread supply in the thread case, the slide 172 upon which the grippers are carried is mounted in the bobbin case retaining arm 138. The slide, together with the gripping jaws, are thus moved away from the thread case with the arm.

To actuate the slide 172 a train of mechanism is provided connecting the slide with the work feed carriage 6. These connections (see particularly Figures 3, 6 and 12) comprise an arm 174 pivotally mounted upon a projection from the thread case retaining arm 138 and provided with a gear segment meshing with a rack at the upper end of the slide 172. An arm 176 is secured to the pivot stud of the arm 174 and is connected by means of a link 178 to the upper end of a lever arm 180. The pivot stud of the arm 180 is journaled in a fixed portion of the machine frame and to this pivot stud is securely clamped a downwardly extending lever arm 182 to the lower end of which is adjustably secured a pivotally mounted block 184 engaging a slot 186 in the feed carriage 6. It will be noted that the link 178 is provided at each end with a universal joint and that the link is in axial alignment with the pivot stud 140 of the thread case retaining arm 138 so that the swinging movement of the retaining arm into and out of operative position is not interfered with.

The movable jaw 170 of the locking thread measuring gripper is in the form of a leaf spring and is secured to the lower end of a lever 188 pivotally mounted on the slide 172. In order to move the jaw 170 towards and from the jaw 168 the lever 188 is extended upwardly beyond its pivot and is provided with a roll engaging a vertical slot in a cross slide 190 mounted in the thread case retaining arm 138. As providing a simple and efficient means for reciprocating the slide 190 to open and close the gripper jaws, the slide is provided at one end with a roll 192 which engages a cam groove formed in a block secured to the carrier block 102 of the loop spreader 100.

The operation of the locking thread gripping and measuring mechanism will be clearly under-

stood from an inspection of Figures 13 to 22 which illustrate the position of the gripper jaws with relation to the positions of the shuttle and other thread handling devices during the formation of the stitch. Starting with the parts in the position illustrated in Fig. 14, it will be noted that the grippers 168, 170 are in gripping engagement with the thread at the upper limit of their reciprocating movement, and that the locking thread has been pulled into the work by the action of the take-up, and that the locking thread is taut from the lock to the grippers. At this point in the operation, the gripping jaws grasp the thread with sufficient firmness to accurately determine the location of the thread lock in the work. After the stitch is set, the locking thread gripper moves downwardly to the position illustrated in Figs. 15 and 16, thereby pulling thread from the bobbin and supplying slack thread between the gripper and the work. The grippers remain in this position during continued operation of the thread handling devices, as indicated in Figs. 17 and 18. As the loop of needle thread is spread, as indicated in Figures 19 and 20, the jaws of the thread gripper release the thread and, while the needle loop is being pulled from the shuttle, the gripping jaws in open condition retract to the position indicated in Figures 21 and 22. At this point in the operation, it will be noted that the slack in the locking thread has been taken up by the action of the needle loop on the locking thread, and that the threads are in condition to be pulled into the work. At this point in the operation, the jaws of the thread gripper close on the thread, as indicated in Figure 14, and remain in gripping engagement with the thread while the thread loop is being pulled into the work and the stitch is being set.

The locking thread measuring and gripping mechanism, above described, is well adapted to cooperate alone with the take-up in determining the location of the thread lock in the work. The illustrated machine, however, is also provided with a needle thread pull-off or thread measuring mechanism, and with a thread lock to insure the proper handling of the needle thread and to cooperate with the locking thread measuring and gripping mechanism in securing a uniform appearance of the stitches and the desired location of the thread locks without danger of breaking the thread or injuring the work. This needle thread pull-off and locking mechanism is best shown in Figures 9, 23, 24 and 25. The needle thread pull-off and measuring mechanism comprises a pull-off arm 194 pivotally mounted on the fixed portion of the machine frame and provided, at its lower end, with a thread eye through which the needle thread passes on its way from the supply to the guide roll 156. This pull-off arm cooperates with a thread measuring arm 196 pivotally mounted on a fixed portion of the machine frame and provided at its lower end with an open ended loop through which the eye of the pull-off lever 194 is arranged to pass. The thread measuring arm 196 is connected to the presser-foot mechanism hereinafter described through a connecting link 198, a bell crank 200, and a connecting rod 202 so that the position of the loop portion which cooperates with the eye of the pull-off is determined by the thickness of the work. The pull-off arm 194 is actuated from the cam shaft through connections hereinafter described to carry the thread eye through the slot of the thread measuring arm so as to pull off an amount of thread determined by the posi-

tion of the thread measuring arm 196, as clearly shown in Fig. 23. This movement of the needle thread pull-off takes place simultaneously with the movement of the take-up in drawing the last needle loop from the shuttle down into the work. At this time in the operation, the needle thread is locked against movement by a thread locking arm 204 pivotally mounted in the machine frame and provided at its lower end with a surface arranged to press the needle thread against the surface of the guide roll 156 and lock the roll with the thread against movement. During the passage of the needle loop around the shuttle, the take-up arms 148 and 150 and the pull-off arm 208 return to the position illustrated in Figure 24 to give up to the shuttle the amount of thread required to enable the loop of needle thread to pass over the shuttle without pulling any more thread from the supply. The thread locking arm 204 is actuated from the cam shaft of the machine, as hereinafter described.

The presser-foot actuating mechanism of the illustrated machine is constructed and arranged to hold the presser-foot yieldingly in contact with the work during the back feed of the feed carriage with the work support and presser-foot, then to force the presser-foot firmly against the work to grip the work between the presser-foot and work support, and to lock the presser-foot firmly in gripping engagement with the work during the work feeding movement of the feed carriage and also during the movement of the needle in retracting from the work. This presser-foot actuating mechanism (see particularly Figure 26) comprises a Horton clutch, the driving member of which is actuated from the cam shaft of the machine, and the driven member of which is connected to the presser-foot. The driven member of the Horton clutch is indicated at 206 and comprises a ring surrounding a three-arm driving member 208. The driven member 206 is connected to the presser-foot by means of a rod 210 extending from a lug on the member 206 to the upwardly projecting arm of the presser-foot lever 12. To allow for the feeding movement of the feed carriage upon which the presser-foot lever is mounted, the link is provided at each end with a universal joint, and at the forward end of the link the universal joint is adjustably secured in a slot in the presser-foot lever. A coiled spring 212 connected to the lug on the member 206 tends to move the member in a direction to force the presser-foot against the work with a yielding pressure. The driving member 208 of the clutch is secured to an oscillating shaft 214 and is provided between its arms with recesses in which are located the gripping rolls 216 of the clutch. The bottoms of the recesses are formed as cam surfaces which, as the driving member is rotated in a clockwise direction causes the rolls to be wedged between the driven and driving members so that the members are locked together and the driven member 206 is positively actuated. This movement of the driven member 206 forces the presser-foot firmly against the work so that the work is clamped between the presser-foot and the work support. Upon the return movement of the driving clutch member 208 in a counter-clockwise direction the rolls 216 are freed from gripping engagement with the two members of the clutch, thus releasing the work and permitting the feed carriage to move to its retracted position. The connecting rod 202 above referred to as a part of the connections between the presser-foot actuating

mechanism and the thread measuring arm 196 is connected at its upper end to a lug 218 projecting from the driven member 206 of the clutch.

The shaft 214 to which the driving member 208 of the Horton clutch is secured is oscillated by connections from the cam shaft 220 of the machine through connections which comprise a cam actuated lever 222 (see Fig. 26) which is pivotally mounted on a long supporting shaft 224 extending forwardly of the cam shaft. The lever 222 is provided with two upwardly extending arms, one of which is provided with a cam follower engaging a groove in a cam disk 226 secured to the cam shaft and the other of which is connected by a link 228 to an arm 230 pivotally mounted upon a shaft 232. The arm 230 forms one member of a toggle joint, the upper member 234 of which extends from the pivotal connection of the link 228 and arm 230 to the outer end of an arm 236 secured to the end of the shaft 214 remote from the driving member 208 of the Horton clutch. The toggle joint formed by the members 230 and 234 is arranged so that the joint is in straightened condition at the limit of the actuating movement of the driving clutch member so that the toggle joint through the driving and driven members of the Horton clutch positively locks the presser-foot in work clamping position.

In the illustrated machine the principal thread manipulating and work feeding devices are actuated from the cam shaft through separate trains of mechanism, in which are provided elements adapted to be disconnected. These movably disconnectible elements are provided in the trains of mechanism for actuating the needle and awl, feed mechanism, take-up, needle threading looper, loop spreader and needle thread lock. Also, the locking thread gripping and measuring mechanism is actuated from the work feed mechanism through connections hereinbefore described, the needle guide is actuated through connections from the needle actuating mechanism, and the needle thread pull-off is actuated through connections from the take-up actuating mechanism. The trains of mechanism between the cam shaft and the spreader, looper, feed carriage, awl, needle and take-up are similar in that each train comprises a lever in engagement with a cam on the shaft and a link movable into and out of engagement with the lever. The cam actuated lever for the spreader is illustrated in side elevation in Fig. 26, and is indicated at 238. This lever and the corresponding levers of the mechanisms for actuating the looper, feed carriage, awl, needle and take-up are pivotally mounted on the supporting shaft 224 which, as above stated, also forms a pivotal support for the presser-foot actuating lever 222. The lever 238 is provided with a cam follower engaging a groove in the cam disk 240, which is mounted with the other cam disks on the cam shaft 220. The detachable link on the mechanism for actuating the spreader is indicated at 242. This link is arranged in substantially horizontal position and, at its forward end, is pivotally connected to the lower end of a two arm lever 244, the upper end of which is connected by a link 246 to the arm 110, hereinbefore described as secured to the pivot stud of the carrier for the loop spreader. Near its rear end and on its under side, the link 242 is provided with a notch 248 adapted to engage a pin 250 projecting from the cam actuated lever 238. While the machine is in operation, the notch 248 is in engagement with the pin 250 so

that the two parts are positively connected and the spreader is actuated from the cam shaft. The link is held in this position by means of a coil spring 252 stretched between a point on the 5 link and a fixed point on the machine frame.

The cam levers and disconnectible links of the trains of mechanism for actuating the looper, feed carriage, awl and needle are similarly arranged and actuated from their respective cam 10 disks on the cam shaft 220. The disconnectible link of the mechanism for actuating the feed carriage is indicated at 34 (see Figure 10). The disconnectible links of the awl and needle actuating mechanisms are indicated at 254 and 256 15 in Figure 5. The cam lever and disconnectible link of the mechanism for actuating the take-up appear in side elevation in Figure 23. The cam actuated lever is indicated at 258 and the disconnectible link at 260. The cam lever 258 is 20 provided with a cam follower engaging a groove in the cam disk 262.

The connections between the detachable links and the spreader and feed carriage have already been described. To actuate the looper, the forward end of the disconnectible link of the looper actuating mechanism is pivotally connected to a lever arm 264 pivotally mounted on a supporting pivot shaft 266 (see Fig. 26) and the upper end of this arm is connected by a link 268 to the looper 30 actuating lever 94, hereinbefore described. To actuate the awl, the link 254 (see Fig. 5) is pivotally connected at its forward end to the downwardly extending arm of a bell crank 270 pivotally mounted in a fixed portion of the machine 35 frame on the supporting shaft 272 and provided at the forward end of its horizontal arm with a gear segment meshing with teeth formed on the awl carrying segment 70. To actuate the needle, the forward end of the link 256 is pivotally connected to the downwardly extending arm of the bell crank 274 pivotally mounted on the shaft 272 40 beside the bell crank 270 and provided at the forward end of its horizontal arm with a gear segment meshing with teeth on the needle carrying segment 72.

The thread finger is actuated from the needle actuating bell crank 274 through a link 276 connecting the lever arm 98 on which the thread finger is mounted to the horizontal arm of the bell crank, as indicated in Fig. 5, and the pull-off 50 for the needle thread is actuated from the lever 166 of the take-up mechanism through a link 278 connecting the upper arm of the lever 166 with the upper end of the pull-off lever 194 (see Figs. 55 23 and 24).

The mechanism for actuating the thread lock (see Figs. 23, 24 and 25) comprises a cam actuated lever 280 pivotally mounted on the supporting shaft 224 and provided with a cam follower bearing against the periphery of a cam 282 on the cam shaft. The cam follower is held in engagement with the cam by means of a coiled spring 284 stretched between the upper end of the lever and a fixed point on the frame of the machine. 60 Upon the forward end of the horizontal arm of the cam lever 280 is pivotally mounted a bell crank 286, the vertical arm of which is provided with a cam follower engaging a cam groove in an arm 288 projecting from the hub of the starting and stopping lever. The horizontal arm of the bell crank 286 is provided with segmental gear teeth meshing with corresponding teeth on the horizontal arm of the thread locking lever 204. With this construction, the thread locking 70 lever 204 is actuated at the proper time during 75

the operation of the machine, but upon stopping the machine the locking lever is moved into inoperative position out of contact with the thread guide roll 156 by the action of the cam groove on the bell crank 286. 5

The supply of needle thread is held in a container (not shown) of well-known construction. From this container, the thread leads through the usual wax pot to the needle thread measuring and pull-off mechanism and then to the thread 10 guide roll 156. In its passage from the guiding roll 156 to the take-up roll 152 (see Fig. 9), the thread passes through an eye in the end of an auxiliary take-up arm 290 projecting from a hub mounted on the supporting stud of the roll and 15 acted upon by a spring 292 coiled around the hub and connected at its opposite ends to the arm and to the stud. This auxiliary take-up arm is useful in controlling slack in the thread given up by the take-up and more particularly 20 while the needle loop is being spread by the loop spreader. The cam shaft is driven through intermeshing spiral gears from a cross shaft 294 25 on which is mounted a loose pulley 296 (see Fig. 1) which is constantly rotated by a belt passing over the pulley and over a pulley driven by a motor in the base of the machine. The pulley 296 is provided with a clutch surface arranged to cooperate with a clutch member 298 mounted to rotate with the shaft 294 and to be moved 30 longitudinally of the shaft into and out of engagement with the pulley 296 by a treadle at the base of the machine.

The shuttle is rotated at a uniform speed 35 through connections from the cross shaft 294 comprising a vertical shaft 300 which is driven from the shaft 294 through intermeshing spiral gears 302 and which drives the shaft 304, to which the shuttle driver 132 is secured, through intermeshing spiral gears 306. The gears through 40 which the shuttle is driven are proportioned to impart two rotations to the shuttle during each rotation of the cam shaft.

The nature and scope of the present invention 45 having been indicated, and a machine embodying the several features of the invention having been specifically described, what is claimed is:

1. A lockstitch shoe sewing machine having, in combination with the other stitch forming and work feeding devices, a hook needle, a locking 50 thread case, a loop taker for passing a loop of needle thread over the locking thread case, means for pulling the needle loop from the thread case and into the work to set the stitch, a locking thread measuring device comprising thread gripping jaws, and means for opening and closing the jaws and for reciprocating the jaws along the lead of the thread timed to draw thread from the thread case prior to the pulling of the needle loop from the loop taker and to be in 55 gripping engagement with the thread while the stitch is being set.

2. A lockstitch shoe sewing machine having, in combination, with the other stitch forming and work feeding devices, a hook needle, a locking 65 thread case, a loop taker for passing a loop of needle thread over the locking thread case, means for pulling the needle loop from the thread case and into the work to set the stitch, a locking thread measuring device, and means for actuating said device during the formation of each 70 stitch to pull from the thread case a length of thread varying with variations in the length of the stitches.

3. A lockstitch shoe sewing machine having, 75

in combination with the other stitch forming and work feeding devices, a hook needle, a locking thread case, a loop taker for passing a loop of needle thread over the locking thread case, means for pulling the needle loop from the thread case and into the work to set the stitch, a locking thread measuring device, and connections between said device and the work feeding mechanism for actuating said device to pull a length 10 of thread from the thread case during the formation of each stitch.

4. A lockstitch shoe sewing machine having, in combination with the other stitch forming and work feeding devices, a hook needle, a locking thread case, a loop taker for passing a loop of needle thread over the locking thread case, means for pulling the needle loop from the thread case and into the work to set the stitch, a locking thread measuring device comprising thread gripping jaws, and means for reciprocating said jaws along the lead of the thread to pull a length of thread from the thread case during the formation of each stitch.

5. A lockstitch shoe sewing machine having, in combination with the other stitch forming and work feeding devices, a hook needle, a locking thread case, a loop taker for passing a loop of needle thread over the locking thread case, means for pulling the needle loop from the thread case 30 and into the work to set the stitch, a locking thread measuring device comprising thread gripping jaws, and means for actuating the jaws during the formation of each stitch to draw thread from the thread case and to be in gripping engagement with the locking thread while the stitch is being set.

6. A lockstitch shoe sewing machine having, in combination with the other stitching forming and work feeding devices, a hook needle, a locking thread case, a loop taker for passing a loop of needle thread over the locking thread case, means for pulling the needle loop from the thread case and into the work to set the stitch, a locking thread measuring device, means for actuating said device to pull a predetermined amount of thread from the thread case during the formation of each stitch, a needle thread measuring mechanism, and means for actuating said mechanism during the formation of each 50 stitch to pull from the needle thread supply a length of thread determined by the thickness of the work, a needle thread locking device, and means for actuating said device to lock the thread while the stitch is being set.

55 7. A lockstitch shoe sewing machine having, in combination with the other stitch forming and work feeding devices, a hook needle, a locking thread case, a loop taker for passing a loop of needle thread over the locking thread case, means for pulling the needle loop from the thread case and into the work to set the stitch, means for pulling a predetermined amount of locking thread from the thread case during the formation of each stitch, a needle thread measuring mechanism, and means for actuating said mechanism during the formation of each stitch to pull from the needle thread supply a length of thread for use in a stitch, a needle thread locking device, and means for actuating said 60 device to lock the thread while the stitch is being set.

8. A lockstitch shoe sewing machine having, in combination with the other stitch forming and work feeding devices a hook needle, a locking thread case, a loop taker for passing a loop of

needle thread over the locking thread case, means for pulling the needle loop from the thread case and into the work to set the stitch, means for pulling a predetermined amount of locking thread from the thread case during the formation of each stitch, a needle thread measuring mechanism, and means for actuating said mechanism during the formation of each stitch to pull from the needle thread supply a length of thread for use in a stitch. 5

9. A lockstitch shoe sewing machine having, in combination, a hook needle, a thread case, a loop taker surrounding the thread case arranged with the thread case to provide access from the front of the machine to a supply of locking thread in the thread case, and a locking thread measuring device comprising gripping jaws acting directly in front of the thread case during the formation of each stitch to draw thread from the thread case. 10 15

10. A lockstitch shoe sewing machine having, in combination, a hook needle, a thread case, a loop taker surrounding the thread case arranged with the thread case to provide access from the front of the machine to a supply of locking thread 20 in the thread case, a locking thread measuring device comprising gripping jaws acting directly in front of the thread case during the formation of each stitch to draw locking thread from the supply, and guiding means on the thread case for supporting the locking thread in a position to be grasped readily by the gripping jaws during their thread drawing movements. 25

11. A lockstitch shoe sewing machine having, in combination, a hook needle, a thread case, a loop taker surrounding the thread case arranged with the thread case to provide access from the front of the machine to a supply of locking thread 30 in the thread case, a locking thread measuring device comprising gripping jaws acting directly in front of the thread case during the formation of each stitch to draw thread from the thread case, and means for moving the gripping jaws away from the front of the thread case to render 35 the thread case accessible. 40

12. A lockstitch shoe sewing machine having, in combination, a hook needle, a thread case, a loop taker surrounding the thread case arranged with the thread case to provide access from 50 the front of the machine to a supply of locking thread in the thread case, a locking thread measuring device comprising gripping jaws acting directly in front of the thread case during the formation of each stitch to draw thread from the thread case, means for moving the gripping jaws away from the front of the thread case to render the thread case accessible and mechanism for actuating the gripping jaws comprising connections arranged to remain connected when the gripping jaws are moved away from in front of the thread case. 55

13. A lockstitch shoe sewing machine having, in combination, a hook needle, a thread case, a loop taker surrounding the thread case arranged with the thread case to provide access from the front of the machine to a supply of locking thread 60 in the thread case, a locking thread measuring device comprising gripping jaws acting directly 70 in front of the thread case during the formation of each stitch to draw thread from the thread case, means for moving the gripping jaws away from the front of the thread case to render the thread case accessible, and manually operated 75

means for holding the gripping jaws in front of the thread case comprising a latching member.

14. A lockstitch shoe sewing machine having, in combination, a hook needle, a thread case, a loop taker surrounding the thread case arranged with the thread case to provide access from the front of the machine to a supply of locking thread in the thread case, a locking thread measuring device comprising gripping jaws acting directly in front of the thread case during the formation of each stitch to draw thread from the thread case, and means for moving the gripping jaws away from in front of the thread case comprising a pivotally mounted arm on which the gripping jaws are movable.

15. A lockstitch shoe sewing machine having, in combination, a hook needle, a thread case, a loop taker surrounding the thread case arranged with the thread case to provide access from the front of the machine to a supply of locking thread in the thread case, a thread case retaining arm pivotally mounted to swing towards and

from the thread case, and a locking thread measuring device comprising gripping jaws arranged on the arm to grasp the locking thread directly in front of the thread case when the arm is in retaining position and to be moved away from the front of the thread case when the arm is swung away from retaining position.

16. A lockstitch shoe sewing machine having, in combination, a hook needle, a thread case, a loop taker surrounding the thread case arranged with the thread case to provide access from the front of the machine to a supply of locking thread in the thread case, a thread case retaining arm pivotally mounted to swing towards and from the thread case, a locking thread measuring device comprising gripping jaws arranged on the arm to grasp the locking thread directly in front of the thread case when the arm is in retaining position, yielding means for moving the arm away from the thread case and a latch for holding the retaining arm in retaining position.

BERNARD T. LEVEQUE.
